UNITED STATES PATENT OFFICE.

SAMUEL L. ALLEN, OF CINNAMINSON, NEW JERSEY.

DESIGN FOR A WHEEL.

SPECIFICATION forming part of Design No. 17,412, dated June 28, 1857.

Application filed February 19, 1857. Serial No. 228,262. Term of patent 14 years.

To all whom it may concern:

Be it known that I, SAMUEL L. ALLEN, of Cinnaminson, Burlington county, State of New Jersey, have invented and produced a new and original Design for Wheels, of which the following is a true and complete specification, reference being had to the accompanying drawings, forming a part of this specification.

Figure 1 is a side elevation of my design. Figs. 2, 3, and 4 are views of substantially the same design.

The leading feature of my design consists in an open star-shaped figure which surrounds the hub of the wheel, the center of the star being placed concentrically within the wheel, and each point of the star terminating in a spoke which extends from the point of the star to the periphery of the wheel, as shown in the drawings.

It will be noticed that I have shown in Figs. 1 and 2 a hexagonal star, while in Figs. 3 and 4 I have shown a pentagonal star.

In the drawings, A is the periphery or tire of the wheel. B B are the spokes. C is the hub. D is the star.

I claim—

The design for a wheel herein shown and described, the same consisting of a star-shaped figure concentrically surrounding the hub of the wheel and having a spoke extending from each of the several points of the star to the periphery of the wheel.

In witness whereof I have hereunto set my hand.

SAML. L. ALLEN.
